(57) **CLAIM**

I claim the ornamental design for a lifting fixture for an aircraft, as shown and described.

DESCRIPTION

FIG. 1 is a perspective view of the present invention showing a landing gear cup in the foreground and a jack attachment cylinder in the rear with cap on top of cylinder. FIG. 2 is perspective view of the present invention showing the jack attachment cylinder in the foreground and the landing gear cup in the rear.

FIG. 3 is a plan view of the present invention; and, FIG. 4 is a perspective view of the present invention as used to lift an aircraft landing gear, with a jack in dotted lines in the foreground connected to the attachment cylinder and the cup supporting an aircraft landing gear, also shown in dotted lines.

The broken line showing of the portions of the aircraft is for illustrative purposes only and forms no part of the claimed design.
